(57) **CLAIM**

The ornamental design for a tablet computer, as shown and described.

DESCRIPTION

FIG. 1 is a front/right-side/top perspective view of a tablet computer showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front/right-side/top perspective thereof showing a stored keyboard removed.

The broken lines shown in the drawings represent portions of the tablet computer that form no part of the claimed design.

1 Claim, 7 Drawing Sheets
